WALTER SABIN MCKINNEY, OF CHICAGO, ILLINOIS.

STAMP-STEM.

SPECIFICATION forming part of Letters Patent No. 701,077, dated May 27, 1902.

Application filed September 23, 1901. Serial No. 76,281. (No model.)

To all whom it may concern:

Be it known that I, WALTER SABIN MCKINNEY, of the city of Chicago, county of Cook, and State of Illinois, have invented certain new and useful Improvements in Stamp-Stems, of which the following is a specification.

This invention relates to improvements in stems for stamps of that type used for reducing or crushing rock, ores, and the like, and refers more specifically to stems adapted for actuation to lift the stamp attached thereto by means of a cam or wiper.

Among the objects of the present invention are to provide a construction in stems of this character which will dispense with the cam-block as a separate attachment, to provide a sectional construction in which the stem is composed of two or more interchangeable members which may be variously arranged both for the purpose of prolonging the life of the stem as a whole and also to enable either part to be replaced in case of necessity for repair or renewal, and in general to provide a simple and improved construction of the character referred to.

The invention consists in the matters hereinafter described, and more particularly pointed out in the appended claims, and the same will be readily understood from the following description, reference being had to the accompanying drawings, in which—

Figure 1 is a view principally in elevation, but with the socketed end portion of one of the members shown in axial section. Fig. 2 is a view similar to Fig. 1, taken at right angles thereto, the lower end of the lower members being broken away to reduce the size of the figure; and Fig. 3 is a lower end or plan view of one of the stamp-stem members.

It has been usual heretofore to make stamp-stems of this general character in a single piece and to mount thereon a cam-block, which was held in position intermediate the length of the stamp-stem by means of suitable keys or keying devices. These stamp-stems are of massive and heavy construction, designed to lift dies or heads weighing from one thousand pounds upward, and the stamp as a whole is usually lifted by means of a cam or wiper and allowed to fall by its own weight. The repeated impact results in rapidly crystallizing the metal of the stamp-stem, and es-

pecially the lower end portion thereof, which is in immediate engagement with the stamp-head or die, so that notwithstanding these 55 stamp-stems be made of the best and toughest forging obtainable they are comparatively short lived. It has heretofore been common to so construct these stamp-stems that they were reversible, or, in other words, 60 so that either end might be attached to the stamp-head or die. This has been the most approved and durable construction heretofore known, and with this construction it has always, so far as I know, been the practice to 65 employ an attachable cam-block mounted upon the stem intermediate its length and capable of being detached and reversed to correspond with the reversal of the stem. In practice it is impossible to secure cam-blocks 70 of this description upon the stem with sufficient security and immovability to prevent their being disarranged or the retaining devices broken in the course of extended use. This objection is so serious that in mills employing a series of a dozen or more stamps in 75 regular operation a large part of the time of an operator is required to readjust and keep in order these stamp-stems. By means of my present invention I overcome these objections 80 to a large extent, if not entirely.

Referring to the drawings, 1 designates as a whole a stamp-stem, which is provided at one end with an enlarged socket portion 2, forming one end of the section and provided 85 with a lower end surface 3, adapted to form a shoulder or cam-surface for the engagement therewith of a cam or wiper 4. In the preferred construction the socket portion 2 is made upwardly tapering or enlarged from the 90 body of the stem downwardly to its lower end, so as to provide the relatively wide annular flat cam-surface 3, hereinbefore referred to. Within the portion 2 is formed a tapered socket adapted to receive the correspondingly shaped or tapered upper end 5 of a precisely similar section. The socket is made somewhat deeper than the tapered end portion 5 of the interfitting stem-section will enter initially, so that said tapered end may 100 wedge within the socket, and thus hold the stem-sections or the stem-section and a corresponding shank upon the die or stamp-head in wedged frictional engagement. It is found

in practice that by making the socket and interfitting shank properly tapered the parts will be held together fast enough for all practical purposes and that instead of tending to loosen the joint will constantly tend to become more and more rigidly united during the use of the stem. In use I employ two such stem-sections, as A B, the lower of which is engaged with the stamp-head or hammer, while the upper is similarly engaged with the upper end of the lower stamp-section. The cam-shaft 9, upon which the wiper 4 is mounted, is arranged transversely to the stem and at one side of the upper end portion of the lower member, so as to support the wiper immediately underneath the overhanging cam-surface 3, formed upon the lower end of the upper section, as shown clearly in the drawings. When thus arranged, it will be obvious that the rotation of the wiper will serve to alternately elevate and drop the stamp as the shaft rotates.

In order to enable the stem-sections to be forced apart or separated when it is desired to rearrange or replace one or the other, each section is provided with a transverse opening or aperture 6, arranged in position to intercept the upper end of the socket 8, within which aperture a tapering drift may be driven, so as to engage the upper end of the interfitting stamp-shank wedge fashion and start the latter out of the socket.

While I have herein-referred to the invention as embodied in a stamp-stem, it is to be understood that the term "stamp" should be construed as equivalent to the word "hammer" in its broader sense, it being obvious that the essential features of the invention are applicable to any drop-hammer in which the repeated impact tends to crystallize and rapidly weaken the part of the stem directly engaged with the hammer-head, and particularly in such cases where a cam or wiper is arranged to act upon a cam-block or cam projection located upon the stem at a point intermediate its length. I do not, therefore, wish to be limited to the precise details of

construction shown except to the extent that the latter are made the subject of specific claims.

I claim as my invention—

1. A stem for stamps and analogous drop-hammers consisting of two or more sections adapted to be united in extension of each other, each section being adapted for connection with a hammer or stamp-head and being adapted at its opposite end for engagement with a similar stem-section, whereby said stem-sections may be interchangeably arranged, as and for the purpose set forth. 5c 6c

2. A stem for stamps and analogous drop-hammers comprising two sections united in extension of each other, the upper member being constructed to telescope on the lower member and a cam-surface formed upon the lower end of the telescoping member, as and for the purpose set forth. 6c

3. In combination, a stamp-stem comprising two sections adapted to be united in extension of each other, each comprising an enlarged and socketed lower end portion and a tapered upper end portion adapted for engagement with a socket similar to that at its lower end, a cam-surface upon the lower end of each stem-section and a cam or wiper located adjacent to one side of the stamp-stem and immediately below the lower end of the upper stem-section in position to engage the cam-surface thereof. 7c

4. As a new article of manufacture, a stamp-stem section comprising a main body portion provided at one end with an enlargement provided with an inwardly-tapering axially-disposed socket, a transverse drift-aperture intersecting the upper end of said socket, a cam-surface formed at the lower end of said enlargement and a tapered opposite end portion adapted for engagement with a socket substantially similar to that provided in the opposite end of said section. 8c
